UNITED STATES PATENT OFFICE.

WILLIAM CAIRNS, OF ELYRIA, OHIO, ASSIGNOR TO THE ELYRIA IRON AND STEEL COMPANY, OF ELYRIA, OHIO, A CORPORATION OF OHIO.

TUBE-FORMING APPARATUS.

SPECIFICATION forming part of Letters Patent No. 734,300, dated July 21, 1903.

Application filed March 2, 1903. Serial No. 145,697. (No model.)

To all whom it may concern:

Be it known that I, WILLIAM CAIRNS, a citizen of the United States, residing at Elyria, in the county of Lorain and State of Ohio, have invented a certain new and useful Improvement in Tube-Forming Apparatus, of which the following is a full, clear, and exact description, reference being had to the accompanying drawings.

10 The invention is an improved organization of mechanism by which a strip of metal—"skelp," as such a strip is technically termed—is bent longitudinally into tubular form.

15 The object is to provide comparatively simple mechanism by which this work may be effectively performed with the result of producing a truly cylindrical tube.

The invention may be here summarized as 20 consisting in a combination of parts shown and hereinafter described, and pointed out definitely in the claims.

In the drawings, Figure 1 is a sectional side elevation of mechanism embodying the invention. Fig. 2 is a plan view of the former E and mandrel-bar F and part of the guide K. Fig. 3 is a bottom plan view of the cover-plate of the former. Fig. 4 is a plan view of the bottom plate of the former. Fig. 5 is a 25 side elevation of the former. Fig. 6 is a transverse sectional view of the guide K in the plane indicated by line 6 6 of Fig. 1. Fig. 7 is a transverse sectional view in the plane indicated by line 7 7 of Fig. 1. Figs. 8, 9, 30 10, 11, 12, 13, and 14 are transverse sectional views of the former in the planes indicated by lines 8 to 14, inclusive, of Fig. 2. Fig. 15 is a transverse sectional view on line 15 of Fig. 1.

40 Referring to the parts by letters, A and B represent two forming-rolls, which are mounted in suitable housings.

C and E represent two driven finishing-rolls, which are likewise mounted in suitable 45 housings, and E represents a former, which is suitably supported between these pairs of rolls and in such relation thereto that the skelp after being initially bent by the rolls A and B passes into the mouth of the former E and after being still further bent within the

former passes from the delivery end thereof into the embrace of the finishing-rolls.

K represents a guide for delivering skelp properly to the rolls A and B. As shown, it is a trough-like plate having a cover k, which 55 is clamped thereon.

H and J represent reducing and feeding rolls by which the skelp is reduced to the proper thickness and is delivered to and moved through this guide. These rolls H 60 and J and guide K are not, however, essential to the operation of the other parts of the mechanism. The strip might be fed by hand into the embrace of the rolls A and B.

The rolls A and B are formed with faces 65 which are respectively concave and convex, and these rolls are so placed relative to each other that the "pass" between them is of the shape in which it is desired to initially bend the skelp. In the construction shown the 70 middle part of the face of the convex roll is substantially cylindrical; but the sides thereof are curved in arcs of something less than ninety degrees of the same radius as the finished tube is to be, and the concave face of 75 the other roll is similarly formed.

In the face of the roll A is an annular groove a, located midway between the sides of the roll. A bar F, which is flattened at one end, passes between the rolls A and B and fits and 80 substantially fills this groove. The end of this bar, which lies upon the receiving side of these rolls, is anchored preferably by being clamped to a bar k², which is secured to the guide K, and this end of this bar is bevelled or curved substantially as shown at f, so as to guide the skelp into the embrace of said rolls. This bar passes through the former E and also between the finishing-rolls C and D and is cylindrical except at its front end, as 85 stated. The part of the bar which passes through the former and between the finishing-rolls serves as the mandrel around which the skelp is bent into tubular form.

The former E consists of a bottom plate e 95 and a cover-plate e'. The bottom plate has in its top face a longitudinal groove e², which at its entrance end fits the skelp as it is delivered from between the two rolls A and B. The cover-plate does not extend up to these 100

rolls, but begins a short distance away from them. This cover-plate is fastened down upon the plate E by any suitable means—as, for example, the wedge M. In the lower face 5 of this cover-plate is a groove e^3 , which, together with the groove e^2 , makes a longitudinal forming-recess whose cross-sectional area is gradually changing and approaching the cylindrical form as it continues toward the 10 delivery end of the former. In fact, said recess at the delivery end is very nearly a true cylinder. A longitudinal rib e^4 is formed upon the cover-plate within this recess, and against this rib the upper side of the mandrel- 15 bar F bends. This rib is of gradually-decreasing width toward the delivery end of the former, and therefore does not interfere with the bending of the edges of the skelp toward each other. In fact, this rib serves a useful 20 purpose in this connection, because it prevents the edges from bending unequally, the rib being so formed that at any point in its length the edges of the skelp, passing through the former, are approximately in contact with 25 both sides of said rib. When the skelp emerges from this former, it is of substantially cylindrical form, and it embraces the mandrel. It then passes between the finishing-rolls, which by their action fix and finish the 30 cylindrical conformation of the tube so formed.

In employing the described mechanism for the purpose stated it is necessary to cut off the corners of the front end of the skelp N, substantially as indicated in Fig. 2 of the 35 drawings, so that said front end may pass into the embrace of the rolls A and B. The part of the bar F on the receiving side of these rolls guides the skelp so that it passes under said bar and between the rolls. The 40 part of said bar between the rolls A and B and the mouth of the former acts both as a guide and a stripper to prevent the skelp

from adhering to the rolls and to carry it properly into the mouth of the former.

Having described my invention, I claim— 45

1. The combination of a pair of driven forming-rolls, the operative face of one roll being convexly curved at its edges and the other roll having in its face an annular groove which is concavely curved at its edges, the 50 middle parts of the operating-faces of said rolls being substantially cylindrical, the concave roll having also an annular groove midway between its edges, with a mandrel-bar which is anchored on the receiving side of 55 said rolls and which passes between said rolls and lies wholly within the groove in the concavely-curved roll, substantially as specified.

2. The combination of a pair of driven forming-rolls whose faces are respectively 60 concave and convex, the convex roll having an annular groove midway between its edges, a pair of driven finishing-rolls, and a former which extends between said pairs of rolls and consists of a bottom plate and a top plate 65 movably secured together, said plates having between them a tubular passage which, at its entrance end, is of substantially the shape of the pass between said rolls, and which gradually assumes a substantially cylindrical form 70 which it has at its delivery end, and a mandrel passing between the forming-rolls and lying wholly within the groove in the convex roll and passing also through said channel and between the finishing-rolls, said mandrel 75 being secured to a fixture on the entrance side of the forming-rolls, substantially as specified.

In testimony whereof I hereunto affix my signature in the presence of two witnesses.

WILLIAM CAIRNS.
